(No Model.)

H. R. HEYL.
STAPLING MACHINE.

No. 444,178.

Patented Jan. 6, 1891.

UNITED STATES PATENT OFFICE.

HENRY R. HEYL, OF PHILADELPHIA, PENNSYLVANIA, ASSIGNOR TO ISAAC FINE, OF SAME PLACE.

STAPLING-MACHINE.

SPECIFICATION forming part of Letters Patent No. 444,178, dated January 6, 1891.

Application filed August 2, 1890. Serial No. 360,737. (No model.)

To all whom it may concern:

Be it known that I, HENRY R. HEYL, of the city and county of Philadelphia, and State of Pennsylvania, have invented an Improvement in Stapling-Machines, of which the following is a specification.

My invention has reference to stapling-machines; and it consists of certain improvements, which are fully set forth in the following specification and shown in the accompanying drawings, which form a part thereof.

The object of my invention is to devise mechanical means for inserting hangers or suspension-loops in books of reference—such as almanacs, railway-guides, &c.—so that the hanger or supporting loops will not in any way prevent the easy and full opening of the pages for the purpose of reference to them, and shall not in any way impede the convenient packing of the books in large quantities for the purpose of shipment. The loop or hanger is attached to the book by being inserted through a hole in the folded edge of the book near the top without piercing the face of any of the pages or covers, and extends over the top edge of the fold of the book and is bent into a triangular shape. The loop is thus loosely supported by the hole through which it is passed and is movable in a plane parallel to the folded pages of the book. When in use for the purpose of supporting the book the loop is drawn out so as to extend beyond the corner, and when the books are to be packed in quantities it is pushed in so that the portion constituting the loop extends between the pages, and the portion upon the outside fits closely against the edges of the book without presenting any objectionable projections or lumps. Such a loop and the method of attaching it to the books are illustrated in the application for Letters Patent of Isaac Fine, Serial No. 358,722, filed July 14, 1890. For inserting loops of this character in the manner described in books or pamphlets with rapidity and precision by mechanical means the present invention is intended. The piece of wire from which the loop is to be made is first formed into a rectangular shape, having two

is fed into position with reference to the folded edge of the book, having one of its short sides located upon one side of the folded edge in line with a hole or perforation which has been previously formed therein and the other short side upon the opposite side of the folded edge. The former of the short sides is then inserted through this hole or perforation and the two ends are bent toward each other, forming the completed triangular loop, passing through the hole or perforation in the folded edge of the book and extending over the top thereof.

In the drawings, Figure 1 is a front elevation of my improved machine looking down upon it at an angle with the feeding-mandrel for supporting the rectangular piece removed. Fig. 2 is a sectional view of the same upon the line *x* *x* of Fig. 1 with the supporting and feeding mandrel in place. Fig. 3 is a perspective view of the guiding-plate for the piece of wire while it is being fed to the book and formed into triangular loops. Fig. 4 is an illustrative view of the different steps in the formation of the rectangular piece of wire into the finished triangular loops; and Fig. 5 is a perspective view, on a reduced scale, of a book or pamphlet with my improved suspension loop or hanger.

A is the base-plate or frame of the machine, to which is secured the inclined frame *B* for carrying the operative parts of the machine.

C is the feeding-mandrel, of rectangular shape and slightly curved for feeding the rectangular pieces of wire *c* to the pusher *D*. This feeding-mandrel *C* is secured at its lower end to a guide-plate *E*, which is connected to the frame *B* by means of screws *e* or in any other convenient manner, leaving an opening *F* between the inner face of the plate *E* and the frame *B* to admit a piece of wire *c*. The upper corner of the plate *E*, to which the feeding-mandrel *C* is attached, is rectangular in shape, corresponding to the shape of the piece of wire *c* and having the slot *a* to allow the piece of wire *c* to pass from the mandrel into the guideway or passage *F*. (See Fig. 3.)

G is an inverted-V-shaped supporting-table for supporting the open book, so as to bring the upper portion of its folded edge over the

plate E, the upper edge of this plate being preferably beveled, as shown at E' in Fig. 3.

H is a guide arranged adjacent to the end of the feeding-mandrel and assists the mandrel in guiding the piece of wire c to the opening or passage F.

D is a pusher pivoted at d to the main frame and having its end D' arranged adjacent to the end of the feeding-mandrel C and in line 10 with the guideway or passage F and adapted to move in front of the end of the mandrel C.

D² is an arm connected with the pusher D, and provided upon its end with a pin d², which is received in a recess i in a reciprocating plunger I, movable in guides I' in the frame B.

Carried by the reciprocating plunger I is a needle or perforator J for perforating the book or pamphlet to receive one of the short sides 20 of the pieces of wire c. The plunger I is operated by a cam I², carried upon the shaft K.

L is a hand-wheel for operating the shaft K. It is apparent that any other satisfactory means may be employed for imparting power 25 to the shaft K.

I³ is a spring for raising the plunger I after it has been operated by the cam I².

M is a hammer guided in the main frame B, arranged adjacent to the plunger I and 30 operated by a cam M' upon the shaft K. The hammer M is raised by a spring (not shown) similar to the spring I³ for raising the plunger I. The under surface of this hammer M is preferably grooved at m, so as to afford better purchase upon the top of the piece of 35 wire c.

N is a clincher, which is movable diagonally in suitable guides n² in the frame B, so that its ends will project into the opening or 40 passage-way F.

O is a pin or stud in the guideway or passage F, located immediately beneath the hammer M. This pin or stud O forms a fixed obstruction to the wire and bends one end of it 45 when the wire is depressed by the hammer M. The end of the clincher N is formed with a clinching-piece n and a long inclined tooth n', between which is a slot N' to allow the clincher N to clear the stud or projection O 50 when it is projected forward.

P is a lever pivoted to the frame B at p, having one end connected to the clincher N and provided upon its other end with a pin P', fitting into a recess Q' in the end of a reciprocating rod Q, the lower end of which is guided in a suitable guide or support q. The upper end is pivoted to a lever R, which is pivoted at r to a bracket S, carried by the main frame.

T is a cam carried by the wheel L for operating upon the lever R to reciprocate the rod Q, and thereby move the clincher N through the connecting-lever P'.

Q² is a spring between the rod Q and the main frame B for raising the rod Q after it has been depressed by the cam T.

To obtain a continuous and rapid feeding

of the pieces of wire c, I prefer to employ an upright bar or stick U, upon which a large number of these pieces c are arranged. This 70 stick or rod corresponds exactly to the shape of the feeding-mandrel C and is placed upon the upper end of the mandrel, so that the wire pieces c may move from the rod or stick U down upon the mandrel to the machine. 75

V is a rod on the main frame of the machine, connected to the feeding-mandrel C for the purpose of giving strength and support to it.

O' is a shutter pivoted to the frame B at o, forming, when closed, a portion of the outer wall of the guideway F for the pieces of wire c. 80

W is the book or pamphlet to which the loops are to be attached.

While I prefer the details of construction 85 which are here shown, I do not limit myself to them, as it is apparent that they may be varied in many ways without departing from my invention.

The operation is as follows: The stick or 90 rod U, provided with the pieces of wire c, is placed in position upon the end of the feeding-mandrels C in the manner shown in Fig. 2, and the pieces of wire which are to be formed into loops and attached to the book 95 are allowed to move down to the end of the mandrel. The end D' of the pusher D is in the position shown in Fig. 1, extending into the guideway or passage F beyond the end of the mandrel. It will be apparent that the 100 last loop of the series of the feeding-mandrels C will be supported by this pusher.

The book or pamphlet to be attached is opened and supported by the table G, with the upper end of its folded edge immediately 105 over the opening between the plate E and the frame B. Upon operating the wheel L the shaft K is rotated. The cam I² depresses the plunger I, causing the needle J to perforate the folded edge of the book at a short distance from the end of the fold. Simultaneously with this, by reason of the connection of the arm D² with the plunger I, the pusher D has been moved out, so as to move its end D' out of the guideway or passage F, allowing the lowermost of the pieces of wire C to move down into it. As the plunger I rises 110 the pusher D moves back, pushing the piece of wire c into position under the hammer M with one of the short sides in line immediately over the hole or perforation which was formed by the needle J and the other short side under or on the inside of the folded edge. Now by the operation of the cam M' the hammer M is depressed. This drives the wire 115 c downward, forcing one of the short sides through the hole or opening in the book, and the other short arm, striking the pin O, is bent upward in the manner shown in Fig. 4 in dotted lines. Immediately after this operation the lever R is acted upon by the cam T, 120 depressing the rod Q and projecting forward the clincher N, so as to bring its end n in contact with the two ends of the short sides of

125 130

the piece of wire *c*, as indicated in Fig. 4, bending them into line with each other and forming the wire into a triangular loop, which is attached to the book or pamphlet through 5 the perforation or hole therein through which one of the sides was inserted. Simultaneously with this operation the long tooth *n'* operates upon the lower angle of the triangular piece, and the pressure thus exerted 10 tends to curve that portion of the wire which extends over the top of the folded edge in the manner shown in Fig. 4. Imparting this curvature to the top portion of the triangular hanger or loop is an important feature, as it 15 causes the wire to pinch the top of the folded edge at the point where it passes over it, so that it will be held in position when the loop is pushed in between the pages of the book or pamphlet.

20 In practice I prefer to impart to the two free ends of the short sides of the pieces of wire *c* slightly more pressure from the end *n* of the clincher than is necessary to bring them in line with each other to compensate 25 for the slight tendency of the ends of the wire to spring outwardly when the pressure is removed. After all of the parts have been operated by the cams *I²*, *M'*, and *T* they are brought back into their normal positions 30 ready to form the next piece of wire into a loop by the action of the springs *I³*, *Q²*, &c.

Having now described my invention, what I claim as new, and desire to secure by Letters Patent, is—

35 1. The combination of a support or table for a book or pamphlet, a guideway or passage extending upon both sides of said table, feeding devices to feed a piece of wire into said guideway or passage with a portion of 40 said wire upon each side of said support, a hammer to drive one portion only of said wire through the book or pamphlet, and a clincher located upon one side of said support to clinch the ends of said wire together.

45 2. The combination of a V-shaped support or table for an opened book or pamphlet with its folded edge upon the ridge of said support, a guideway or passage extending upon both sides of said table, feeding devices to 50 feed a piece of wire into said guideway or passage with a portion of said wire upon each side of said support, a hammer to drive one portion only of said wire through the book or pamphlet, and a clincher located upon one 55 side of said support to clinch the ends of said wire together.

3. The combination of a support or table for a book or pamphlet, a guideway or passage extending upon both sides of said table, 60 a perforator for perforating said book or pamphlet, feeding devices to feed a piece of wire

into said guideway or passage with a portion of said wire upon each side of said support, a hammer to drive one portion only of said wire through the book or pamphlet, and a clincher located upon one side of said support to clinch the ends of said wire together. 65

4. The combination of an inverted-V-shaped support for a book or pamphlet, having an opening or guideway through its ridge, a 70 pusher to push a piece of wire into said guideway or opening with a portion upon each side of the book upon the support, a hammer to drive one portion of said piece of wire through the book or pamphlet, and a clincher to bend 75 the ends of said wire toward each other.

5. The combination of an inverted-V-shaped support for a book or pamphlet, having an opening or guideway through its ridge, a 80 pusher to push a piece of wire into said guideway or opening with a portion upon each side of the book upon the support, a feeding-support for a series of said pieces of wire for feeding them successively to the pusher, a hammer to drive one portion of said piece of wire through the book or pamphlet, and a clincher to bend the ends of said wire toward 85 each other.

6. The combination, with a book-support having a passage or guideway extending 90 through it, of a pusher to push a piece of wire into said guideway with a portion upon each side of said support, a hammer to depress said piece of wire and drive one end through the book upon the support, and a 95 fixed obstruction in said passage-way under said support for bending said piece of wire when it is depressed by said hammer.

7. The combination of the support *G* and hammer *M* with the clincher *N* and stud *O*, 100 said stud being adapted to bend the end of a wire staple into position to be operated upon by the clincher *N*.

8. The combination of the frame *B*, guide-plate *E*, having the slot *a*, the mandrel *C*, 105 pusher *D*, and staple-clinching devices, substantially as described.

9. The combination of a supporting-table for a book or pamphlet, having one of its edges slotted to form a guide or passage way 110 extending into the table through said edge, a pusher to push a bent piece of wire into position with a portion upon each side of said table, and means to bend the free end of said wire into a loop in said slot. 115

In testimony of which invention I have hereunto set my hand.

HENRY R. HEYL.
